UNITED STATES PATENT OFFICE.

WALTER R. TAVERNETTI, OF SALINAS, CALIFORNIA.

ROAD-MAP EXHIBITOR.

Application filed August 11, 1923. Serial No. 656,883.

To all whom it may concern:

Be it known that I, WALTER R. TAVERNETTI, citizen of the United States, residing at Salinas, in the county of Monterey and State of California, have invented certain new and useful Improvements in Road-Map Exhibitors, of which the following is a specification.

This invention relates to changeable exhibitors and has particular reference to a device for exhibiting road maps to the driver of a vehicle when making trips.

The primary object of the invention is to provide a device of the above kind which embraces the desired qualities of simplicity and durability of construction, as well as efficiency in operation.

A further object of the invention is to provide a changeable exhibitor for road maps of the double reel and web type, wherein improved means is provided for moving the web or map strip.

Other objects will appear as the nature of the invention is better understood, and the same consists in the novel form, combination, and arrangement of parts hereinafter more fully described, shown in the accompanying drawings and claimed.

In the drawings, wherein like reference characters indicate corresponding parts throughout the several views,

Figure 1 is a fragmentary view, partly in side elevation and partly in section, showing a map exhibiting device constructed in accordance with the present invention and operatively associated with a casing containing gear reduction mechanism adapted to be driven in a manner similar to the driving of speedometers.

Figure 2 is an enlarged front elevational view of the exhibiting device.

Figure 3 is a side elevational view of the device shown in Figure 2, with the adjacent side wall of the exhibitor casing removed, and

Figure 4 is a rear elevational view of the device shown in Figure 2, with the rear wall of the casing removed.

Referring more in detail to the drawings, the present invention embodies a substantially rectangular casing 5, the top wall of which is provided with depending bearing brackets 6 having a reel 7 journaled therein, and from which the web or road map 8 is unwound. The casing 5 is provided with removable walls for permitting access to the

interior thereof. One of the shafts of the reel 7 projects through one side of the casing where it is provided with a knob 8 by means of which the reel may be turned for winding the map backward if ever found necessary.

The front wall of the casing 5 has a transparent panel 9 through which the map strip may be observed as shown in Figure 2, and this map passes upwardly from the reel 7 around a guide roller 10 where it is suitably journaled at the top of the casing adjacent the front wall of the latter. The map strip passes downwardly behind the transparent panel 9 from the guide roller 10 to and around a further guide roller 11 which is suitably journaled at the bottom of the casing adjacent the panel 9 as is clearly shown in Figure 3.

A pair of spaced bearing brackets 12 of special form are rigidly secured in the bottom portion of the casing 5 behind the roller 11 and this bracket 12 is provided with an upwardly and forwardly inclined longitudinally slotted arm 13 having an entrance slot 14 extending laterally from the upper end of the longitudinal slot which is noted at 15. A driving roller 16 is suitably journaled in and between the bracket 12 beneath the arm 13 and in alignment with the slot 15 thereof, and this roller projects through one side of the casing 5 where it is provided with a knob 17 for its manual operation if found desirable.

A second reel 18 is provided in the casing 5 and has a shaft 19, the ends of which project into the elongated slot 15 of the bracket 12 as shown in Figures 3 and 4. The map strip 8 is adapted to be wound upon the reel 18 as shown in Figure 3, and the portion of the map strip which is wound upon this reel is yieldingly urged into contact with the periphery of the driving roller 16 by means of leaf springs 20, which are preferably fastened to the rear wall of the casing and hook over the ends of the shaft 19. Obviously the reel 18 may be removed by passing the ends of the shaft 19 outwardly through the lug 14 of the bracket arm 13, and it is also apparent that in order to secure a more positive driving action for the rollers 16, the latter will be provided with a covering of rubber or the like for preventing slippage of the same relative to the portion of the road map which is wound upon the roller 18.

In order to prevent the unwinding of the

map too freely of the map from the reel 7, rotation of the latter is resisted in the proper direction, frictionally, by means of a spring brake 21, which frictionally engages the reel 5 7 or the shaft thereof, as shown in Figure 3.

Referring to Figure 1, the driving roller 16 may be suitably actuated at the required speed by means of flexible shafting 22 having one end connected detachably as at 23 10 to the shaft of the roller 16 and having its other end operatively connected to a speed reducing gearing (not shown), the casing of which is generally noted as at 24. The flexible shafting 22 will of course be connected 15 to the driven element of the reduction gearing and the driving element of the latter may be operatively connected by means of a flexible shafting 25 with the front steering and supporting wheel of the motor vehicle 20 in any suitable manner, such as is at present practiced in connection with the driving of speedometers.

The device above described can be set or fastened at any place on the instrument 25 board B of the vehicle or on the steering post so that the driver can readily observe the map as it is moved during the forward travel of the vehicle. The map or guide strip moves downwardly as indicated by arrows in Figure 3, toward the driver, and an indicator 26 is provided upon the panel 9 near the bottom of the casing to indicate the particular part or point on the map at which the vehicle is located during its travel. This 30 is accomplished by properly proportioning the scaling of the map and the speed at which it is driven. Thus, the driver is provided with knowledge of the road for several miles ahead of the point where he is located 35 and besides being valuable as a guide by giving the names of places and points of interest, the map may be illuminated by a small shaded light so that the map will be readily visible when travelling at night over strange 40 highways for advising the driver before- 45

hand of the approach to dangerous curves, railroad crossings and the like.

From the foregoing description it is believed that the construction and operation as well as the advantages of the present invention will be readily understood and appreciated by those skilled in the art. 50

Minor changes may be made without departing from the spirit and scope of the invention as claimed. 55

What I claim as new is:

In a double reel and web road map exhibitor, a casing of substantially rectangular form having a front wall provided with a transparent panel through which the map 60 is to be viewed, a pair of bearing brackets depending from and supported by the top of said casing, a reel journaled in said brackets and adapted to initially receive the map thereon, means for frictionally resisting unwinding movement of said reel, guide rollers at the top and bottom of said casing directly behind said transparent panel and about which the map is adapted to be led from the said reel, a pair of spaced bearing 70 brackets rigidly mounted in the bottom of the casing and having a driving roller journaled therein, means for driving of said roller, arms projecting upwardly from the last named bearing bracket and having longitudinally elongated slots aligned with the shaft of the driving roller, a receiving reel having a shaft with its ends disposed in elongated slots of the bracket arms whereby the receiving reel is free to move toward the 75 driving roller, and yieldable means associated with the ends of the shaft of the receiving reel for urging the latter toward said driving roller, whereby the portion of the map wound upon the receiving reel is in 80 driving contact with the periphery of said driving roller. 85

In testimony whereof I affix my signature.

WALTER R. TAVERNETTI.
